INVENTOR.

Clyde A. Johnson

UNITED STATES PATENT OFFICE.

CLYDE A. JOHNSON, OF SAN DIEGO, CALIFORNIA.

GRADOMETER.

1,398,433.

Specification of Letters Patent. Patented Nov. 29, 1921.

Application filed March 23, 1920. Serial No. 368,140.

To all whom it may concern:

Be it known that I, CLYDE A. JOHNSON, a citizen of the United States, and a resident of San Diego, in the county of San Diego and State of California, have invented a certain new and useful Gradometer, of which the following is a specification.

My invention relates to a gradometer for measuring the inclination of the grade of a roadway more particularly adapted for use as an attachment to a vehicle so that the driver may readily determine the inclination of the grade over which the vehicle is driven and the objects of my invention are: first, to provide a gravity actuated device of this class for readily determining the grade; second, to provide a gravity actuated device of this class, so constructed that the ordinary vibration and short, light tilt of the machine will not affect the indicator and make the needle vibrate; third, to provide a device of this class in which the weight is suspended so that the sides will engage its inclosing walls to prevent slight vibration from moving the indicator needle but permits its revolution upon regular variation of the grade; fourth, to provide a device of this class with a clutch means for holding the weight operating device in inoperative position relatively to the shaft to permit the setting of the indicator needle for different positions of the gradometer on the vehicle; fifth, to provide a device of this class which is very simple and economical of construction, durable, automatic in its action, easy to install and which will not readily deteriorate or get out of order.

With these and other objects in view as will appear hereinafter my invention consists of certain novel features of construction, combination and arrangement of parts and portions as will be hereinafter described in detail and particularly set forth in the appended claims reference being had to the accompanying drawings and to the characters of reference thereon which form a part of this application in which:

Figure 1 is a top plan view of my device; Fig. 2, a side elevational view thereof; Fig. 3, a sectional view through 3—3 of Fig. 1 showing some of the parts and portions in elevation to facilitate the illustration; Fig. 4 is a sectional view through 4—4 of Fig. 3 and Fig. 5 is a sectional view through 5—5 of Fig. 3.

Similar characters of reference refer to

similar parts and portions throughout the several views of the drawings.

The main casing 1, indicator casing 2, main support 3, weight support 4, links 5, 60 weight 6, gear 7, pinion 8, shaft 9, needle 10, dial 11, sleeve 12, shaft 13, handle member 14, handle member 15, pin 16, spring 17, and clutch 18 constitute the principal parts and portions of my gradometer. The 65 casing 1 may be any shape or form desired. I have shown in this case an approximate cube and it is provided with a cover 1^a on one side. Secured in this casing near the opposite side from the cover is a support 3 which is provided with a circular recess 3^a which extends over a large portion of the same in the center thereof and it is provided with a central hole in which is journaled the end of the shaft 13 which 70 extends out through the casing and is provided with a handle member 14 on its outwardly extended end. This shaft is also journaled in the cover member 1^a. Secured to the shaft 13 adjacent the support 3 is 75 a journal member 4^a upon which is revolvably mounted the weight support 4 which is provided with a hub portion 4^b on its one side. This support 4 extends upwardly and is provided with two laterally extended 80 arms 4^c and 4^d upon which are pivotally mounted the upper ends of the link members 5 and to the lower ends of said link members 5 is pivotally connected the weight 6 which is semi-annular in form and adapt- 85 ed to rest in the recess 3^a and provided with slight clearance so that the weight 6 may revolve relatively to the support 3, however upon slight lateral movement the weight 6 would shift sidewise against the 90 inner wall of the support 3 retarding the revoluble movement of the weight with slight movement of the casing 1, thus preventing the vibration of the needle member 10. However when the grade upon 95 100 which the vehicle operates changes, the weight 6 will revolve with the shaft 13 moving the hand thus providing a positive movement of the hand and preventing its vibration unnecessarily. Secured on the 105 shaft 13 is a gear 7 which meshes with a pinion 8. Secured on a shaft 9 which extends out through the front side of the casing 1 and on the outer surface is provided a needle member 10 incased in a casing 2, 110 the casing 1 being provided with a dial 11 provided with characters indicating the

degree of the grade in either direction. The shaft 9 is supported by means of a bracket 9^a. On the shaft 13 between the gear 7 and the casing cover 1^a is a sleeve 12 which serves as a support for holding the gear 7 and weight support in their proper relative position in the casing.

It will be noted that the weight 6 is shown in two parts connected by bolts, however it is obvious that this weight may be made in one piece and supported by the links 5. Mounted in a hole in the support 3 is a pin 16 which is adapted to reciprocate therein. It is provided with a handle member 15 on its outer end and with a spring 17 tending to hold said member outwardly. The inner end of this pin 16 engages the hub member 4^b on the support 4 when pressed inwardly for holding the same from revolving when desired and positioned against the hub portion 4^b is a spring 18 which is secured to the member 4^a and forming a friction clutch member for connecting the member 4^a with the support 5 and weight 6 under ordinary operating conditions but when the pin 16 engages the hub portion 4^b the hub portion 4^b is held from revolving so that the shaft 13 may be revolved without revolving the hub portion 4^b and supports 5 and weight 6, thus it will be noted that by revolving the shaft 13 by means of the handle 14 and with the pin 16 pressed against the member 4^b the indicator needle 10 may be set relatively to the position of the weight 6 as desired thus providing for setting the gradometer indicator so that it may be positioned on varying angles and with different sides up as desired and the indicator set to suit.

Though I have shown and described a particular construction, combination and arrangement of parts and portions I do not wish to be limited to this particular construction, combination and arrangement but desire to include in the purview of my invention the construction, combination and arrangement substantially as set forth in the appended claims.

It is obvious that with this construction there is provided a gradometer in which the weight for revolving the needle with the inclination of the grade is retarded from revolution by engagement with the wall of the support upon short, slight vibration but will revolve in said support showing the grade inclination without needle vibration and that the indicating mechanism may be turned from the outside by the handle member 14 the weight and supports being held from turning by the handle member 15 for

setting the needle properly with the dial 60 relatively to the position of the weight.

Having thus described my invention what I claim as new and desire to secure by Letters Patent is:

1. A gradometer, including a casing having a circular recess, a support pivotally mounted in said recess, a weight suspended on said support in said recess on a parallel axis with said support whereby said weight is adapted for both revoluble and swinging 70 movement in opposite directions against the curved wall of said circular recess in the plane of its normal rotation and gear, means in connection with said weight support for indicating the relative position of said 75 weight support with said casing.

2. A gradometer, including a casing having a circular recess therein, a support pivotally mounted in said recess, a weight suspended on said support in said recess and 80 adapted for both revoluble and lateral movement in opposite direction in the plane of its normal rotation therein and adapted to engage the circular wall of said casing with slight lateral movement of said casing in 85 the plane of its rotation and means in connection with said weight support for indicating the tilting movement of said casing.

3. A gradometer, including a casing, a shaft revolvably mounted in said casing, a 90 supporting member secured to said shaft, link members with the upper ends pivotally connected to said support and a weight pivotally mounted on the lower ends of said links adapted to swing in opposite directions in the plane of its rotation and to engage the curved wall of said casing with slight lateral vibration.

4. A gradometer, including a casing adapted to be secured to a vehicle, a shaft 100 revolvably mounted in said casing, a supporting member secured to said shaft, link members pivotally connected to said support, a weight pivotally mounted on the opposite ends of said links adapted to engage 105 the wall of said casing with slight lateral vibration, a gear secured to said shaft, a grade indicator mounted on the outer surface of said casing and means operatively connecting said indicator with said gear and manually operated means mounted in said casing for engaging said support whereby said support may be held relatively to said casing.

In testimony whereof, I have hereunto set 115 my hand at San Diego, California, this 17th day of March, 1920.

CLYDE A. JOHNSON.
